SWITCH

Max L. Jeffrey, Chagrin Falls, Ohio

Application April 20, 1953, Serial No. 349,737

11 Claims. (Cl. 200—70)

This invention relates to improvements in quick acting switches, and more particularly to a switch of the type where the movement of an external lever connected to a shaft causes the build up and storage of energy by spring means which is applied to a rocker that is held against movement until the energy stored reaches a predetermined amount and the operating lever releases the rocker and the spring causes the rocker to snap to another position. The rocker carries sets of movable contacts which are brought into contact with fixed contacts in its alternate positions.

The present invention also constitutes a switch which has a plurality of fixed contacts that enables a greater versatility of connections into various circuits.

A further advantage resides in the ability to quickly change the switch by movement of the parts to provide a switch that is normally closed or normally open regardless of the movement of the operating lever; one where the making and breaking contacts are in a chamber where the arcing is confined, increasing its effectiveness against fire hazards and one where the circuit connecting screws are disposed for easy access for making connections and cannot interfere with the operating mechanism.

Still other advantages of the invention including economy of construction will become more apparent from the following description of an embodiment thereof, which description is illustrated by the accompanying drawings and forms a part of this specification.

In the drawings:

Fig. 1 is an elevational view of one side of the switch of my invention with the cover plate removed;

Fig. 2 is a sectional view taken on the line 2—2 of Fig. 1;

Fig. 3 is a view similar to Fig. 1 from the opposite side thereof;

Fig. 4 is a fragmentary section taken on the line 4—4 of Fig. 2;

Fig. 5 is an exploded view of the snap action assembly removed from the housing;

Fig. 6 is a fragmentary view of the lower half of the switches showing a modified form of construction;

Fig. 7 is a fragmentary medial section of Fig. 6;

Fig. 8 is a view similar to Fig. 6 with certain parts removed to more clearly illustrate the structure of the other parts;

Figs. 9 and 10 are alternate views showing different arrangement of contacts; and

Fig. 11 is a face view of a modified form of back bearing and return spring plate with the return spring in position; and

Fig. 12 is a side view with the spring removed.

Referring now to the drawings, throughout which like parts are designated by like reference characters, there is illustrated a housing which includes the side walls 10 but wherein the front and back are mostly open to enable easy assembly of the parts, the front and back being closed, after assembly of the parts therein, by cover plates illustrated by the dot dashed lines which are held in place by

2

screws that are threaded into the screw holes 11. The upper end of the housing is provided with a hollow inferiorly threaded boss 12 for the reception of an electric wire conduit. The opening through the boss opens to the interior at the end adjacent to the terminals where the conductors may be connected.

Generally speaking, the switch includes a terminal support for the stationary contacts, a swingable, movable contact carrying member for cooperation with the stationary contacts and a snap action mechanism for swinging the movable contact member quickly between alternate positions.

The fixed contacts are so supported that their conductor attaching ends are convenient to the wire entrance to the housing. The structure of the housing is also such that easy access is had to the wire attaching screws. The support for the contacts is such that certain of the contacts may be omitted if desired, thus extending the versatility of the device. To these ends, a block 15 of insulating material, such as "Bakelite" is provided, being of general arcuate formation, as best seen in Figs. 2 and 3, and bridging the side walls 10. This block is held in position by a large insulating plate 16 located on the rear of the housing and a bar or bridge 14, Fig. 1, located at the front of the housing, the bridge preferably being integral with the housing. Interposed between the bridge and the block is a plate of suitable insulating material. The rear plate seats on ledges 18 formed along the sides of the housing at the rear. The front plate 17 is sandwiched between the block and the front bridging member 14 and the assembly is held together by long screws (not shown) which extend through the rear plate, block and front plate, and are then threaded in holes 21 in the front bridging member 14. The heads of the screws are countersunk in the rear plate. A sheet of insulating material 20 is disposed between the plate 17 and the bridge 14 and extends toward the front of the housing to provide additional insulating protection between the contact screws and the front bridging member, since the bottom ones of these screws are relatively close to the bridging member.

The front and rear faces of the block 15 are provided with vertically extending slots 23 into which the fixed contact carrying strips or bars are inserted prior to assembly, these bars being held in place by the clamping section of the rear holding plate against the bridge. A sheet of insulating material 20 between the bridge and the part 17 prevents shorting of front contacts.

The fixed contact bars are held against vertical movement since they are provided with notches 25 which allow the contact strips to protrude over the top and bottom of the stationary contact carrying block 15.

The block 15, together with its supporting plates and bridging member 14 provides a generally horizontal partition, dividing the housing into two chambers 26 and 27. The upper chamber 26 has the connector ends of the fixed contact bars and the lower chamber 27, has the contact carrying ends. This is an additional precaution against the hazards of fire due to arcing during the break of the contacts since the two chambers are thus isolated from each other.

The ends of the contact strips are all bent to provide seats 28 which are threaded for the reception of the conductor holding screws 29, which thus all face in the same direction toward the front of the housing for easy installation of the wires.

The lower ends 31 of the contact strips, considering the outermost ones, are bent inward at an angle of approximately 45 degrees and carrying suitable contacting surfaces 32 of silver, tungsten or other suitable metal as may be desired. There is also provided a fixed central contact 33 formed in the shape of a V, each side of which

has contacts and which face generally toward the outer contacts. It will thus be seen that there is provided two center contact strips, one at the front and one at the rear, and that these are flanked by two pairs of outer contacts at the sides, thus providing three pairs of contacts, and thereby enabling connection to at least three separate circuits, since each pair of contacts may be connected into a separate circuit.

Each of the pairs of contacts is closed by a movable contact, each of which is in the form of a bar and connects the front one of the pairs of contacts to the back one. In the embodiment shown, this is effected by two sets of contact bars each set comprised of two bars and each of the two sets operating between one set of the side contacts and the center contacts. These bars are carried by a rocker or swingable member 45 of insulating material which may be swung to alternate positions to effect the foregoing.

As can best be seen in Fig. 1, the lower part of the housing has formed integral therewith a cross beam 40, the center of which is provided with a boss 41 which has a horizontally extending bore 42, Fig. 2, that receives a pin 43. The pin pivotally supports the contact carrier or rocker 45 since it extends through a bore in the rocker. A head 44 on the pin engages the rocker and holds it against the boss 41 while the other end extends through the boss and is secured by a suitable lock 46. In the embodiment shown, the pin is upset slightly beyond the washer to hold the same in place. It will be apparent, however, that the preferred construction contemplates a C washer in a groove on the pin. In any event, it should be understood that the rocker is free to rock on the pin 43. It will also be appreciated that, although the cross beam 40 is shown as being integral with the housing, it could very well be a separate part if desired.

The rocker itself includes an upper head portion 50 disposed above the beam 40 which supports the contact bars and a lower operating stem 51 disposed below the beam and in engagement with and forming a part of the snap action mechanism which cooperates with it to perform the swinging motion previously mentioned.

As can best be seen in Fig. 2, the rocker, in longitudinal cross section, includes a thin upper part extending above a somewhat thicker mid-section, the lower portion having a more complex formation which will be more fully described later.

The upper portion 50 as stated is thin enough so that it may move freely in the space between the fixed front and back contacts. This head portion is also of general T shape with the top surface curved to conform to the arch of the fixed contact carrier 15 (Fig. 3), since it swings from one side of the housing to the other below that arch. It is also provided with two openings 52 extending transversely through the head from the front to the rear. These openings 52 are of generally rectangular formation, except that the end walls may be curved to conform to the curved shape of the movable contact bars 55.

As can best be seen in Fig. 2, the movable contact bars 55 are generally H shaped, and may be made of metal having a concave-convex cross section. They are inserted in pairs in the openings 52 with the convex side facing, one toward the side contacts and the other toward the center contacts, and are held by springs 56, seated resiliently against the curved end walls. Each of the springs is seated on lugs on the concave side or is, in this case, the ends of the spring may be bent outward and engage in holes in the bars. When lugs are used for mounting the springs, the springs may be opposite the enlarged ends. As shown in the drawings, however, one spring for each set of contacts will suffice. Preferably, the ends are made of a suitable contact metal, but they may also have contacts carried thereby if desired. It will be noted that the contacts being convex when moved into engagement with the fixed contacts provide a rocking

action which assists in making a good contact of a line variety which also insures longer life. The contacts are sufficiently long that they each are able to bridge the gap between each of the front and rear fixed contacts

5 of the pairs of contacts.

It is preferred that the angle of inclination of the fixed contacts be such that when the movable contacts engage them they are drawn across the fixed contacts with a wiping action. This is best effected by fixing the 10 plane of the fixed contacts so that it passes to one side of rather than through the center of rotation of the rocker.

The swinging of the rocker is accomplished by a mechanism which cooperates with the lower end of the rocker and which includes means whereby energy is stored up and, upon the movement of a lever, is suddenly released to cause the rocker to be snapped from one position to another. Provision is made for a certain amount of over-travel of the operating lever in order to prevent damage to the mechanism and also increase the versatility of its use.

In order to enable the foregoing to be effected, a shaft 60 is provided. The shaft is formed with a serrated stem 61 which is split and has an expansion screw 62 threaded in the split end to enable a lever which may take many different forms, depending on its use, to be securely held on the end of the shaft. Adjacent the stem 61 there is provided a bearing surface 63 which is rotatably journaled in a bearing 64 of the boss 65 on the lower end of the housing.

The end of the shaft 60 remote from the stem 61 is provided with a short bearing surface 67 which is journaled in a bearing plate 68. The plate 68 is supported on ledges 69 formed on the sides of the housing, the plate being provided with wing shaped arms 70 which seat on these ledges and the pointed ends 71 of which abut the screw receiving bosses 72 and the lower surfaces 73 of which rest on the shoulders 74 formed on the housing. It will thus be seen that the plate is held against lateral movement in the housing and is held in place in the housing by the back plate 9.

The shaft 60, Fig. 5, is provided with two key ways 80 diametrically opposite each other that enable it to drive a cam element 83 and a spring operating element 86. In order that a better understanding may be had, it is pointed out that the shaft drives the spring operating element 86 which in turn moves the spring 90 which engages and tends to move the rocker. The rocker cannot move, however, because it is held by one of the dogs 95. Energy is therefore stored up in the spring until such time as the cam 83 releases the dog from engagement with the rocker at which time the spring moves the rocker.

The mechanism for effecting this motion is shown in Fig. 5, the parts being arranged in the order of their assembly. As can be seen in Fig. 2, the cam element 83 is disposed next to the key 82 which is engaged in a groove 82' in the shaft to hold the shaft in the housing. The C washer 82 bears against the inner surface of the boss 65. The cam element 83 has lugs 84 which engage in the grooves or keyways 80 extending longitudinally of the shaft. The cam element is thus disposed opposite to the longer end of the rocker and in alignment with the dogs or pawls 95 which are supported on pins 96 having reduced ends 96' and extend into bosses 100 in the housing (Figs. 4 and 5), on opposite sides thereof. The dogs 95 are generally bell crank shaped having arms 95' that are arranged to engage the flat side or pawl seat surfaces 101 on the end of the rocker stem 51. The other 60 arm 97 of the dog has a cam engaging projection 98 which engages with the extremity of the dwell 99 on the cam element 83. The dog is held with the projection 98 pressed against the cam element 83 and with the arm 95' opposite the face 101 of the rocker by a spring 103 which is disposed on the projection 104 on the dog and the other

end of which engages the housing wall, as can best be seen in Fig. 4. There are two of these dogs disposed on opposite sides of the housing, and, if the cam element 83 is rotated clockwise, the edge of the dwell 99 (Fig. 4) rotates the right hand dog counter clockwise and gradually removes the end 95' from engagement with the face 101 on the rocker arm.

In the meantime, spring pressure is being applied to the rocker arm tending to rotate it toward the right (Fig. 4). The means for applying the spring pressure includes the spring operating element 86 which has lugs 86' also engaged in the keyways 80. This element 86 is provided with a pair of oppositely extending arms on its upper end, one acting as a rotor spring lever 105, and the other acting as a rotor return lever 105'. As can best be seen in Fig. 5, this element may and preferably is made in two parts which are placed back-to-back as shown. They can be welded together if desired but this is not essential. It is held in spaced relation from the cam element 83 by a washer 106 and spacer 107. Disposed about the spacer 107 is the spring 90 which includes the circular body and two upwardly extending spaced arms 109. The arms 109 extend upward toward the pivot of the rocker and engage a downwardly extending boss or projection 110 on the rocker on opposite sides thereof. This boss preferably has curved sides for tangential engagement with the inner surface of the spring arms 109. The arm 105 on the spring operating element 86 extends between the arms 109 of the spring 90 below the boss 110. Preferably, the spring 90 is formed so that the arms, in the unassembled state are relatively close together, and when assembled they engage the boss 110 with some pressure.

It can be seen that where the shaft is rotated counter clockwise as viewed in Fig. 3, the arm 105, being between the arms 109 of the spring, forces one of the arms away from the boss 110 which increases the pressure of the other arm against the boss and tends to rotate the rocker. This rotation is prevented, however, because the dog on the left has its arm 95' engaging the face 101 on the end of the rocker.

At the same time, the cam element is being rotated by the shaft and the dwell 99 of that element is engaging the projection 98 and the arm 95' is gradually being drawn downward from contact with the face 101. Eventually, the rotation of the cam is such that the dog rides on top of the dwell 99 and at this time the projection 95' is withdrawn from the abutting relation to the face 101. The maximum tension of the spring is thus present at the time the rocker is released. This movement may be considered gradual, although it may take place in a relatively short time depending upon the rapidity of movement of the shaft 60. The arms 109 of the spring are forced further apart and when the dog releases the rocker they come back together snapping the rocker quickly to the left (Fig. 3). This, of course, "breaks" the left hand and center right contacts and "makes" the center left and right hand contacts.

At the same time, the other dog (the one on the left as viewed in Fig. 3) is now moved counter clockwise by the spring 103 and its projecting arm 95' is brought up on opposition to the face 101 on the left side of the rocker arm.

As can best be seen in Fig. 4, the flat on the side of the rocker stem engages a flat 100' on the boss 100 which thus enables the housing wall to take up the shock at the end of the swinging movement. It will also be noted that the thinness of the head of the rocker reduces the weight which, in turn, reduces its tendency to bounce.

A return spring 130 which is disposed about a spacer 131 journalled in the shaft 60 abutting the spring operating element 86 and which cooperates with the back shaft bearing plate 68 and the spring operating member 86 to urge the member 86 in one direction or the other depending upon the manner in which the return spring is

assembled in relation to the back plate 68 and the member 86.

The spring 130 is also provided with arms 132 which are normally diverging as shown in Fig. 5. During assembly, it is so assembled with the other parts that one of the arms 132 engages a lug 133 or 134 on the back bearing plate, and the remaining arm will engage the arm 105' on the member 86. This brings the arms 132 closer together and the outward force of the arm against 10 the lug 133 or 134 and the arm 105' has a tendency to move the member 86 in one direction or the other depending on which side the spring is placed.

It will be appreciated that if this spring is removed, the rocker will remain in one extremity or the other until 15 the shaft 60 is rotated by some external effort, but that when in place, the return spring 130 causes the rocker to be automatically returned to its original position.

A center lug 135 on the back plate 68 engages the spring arm after it has forced the operating member 86 20 back to its original position, thereby maintaining the shaft in a pre-operative relationship and removing the pretravel portion of the stroke of the shaft so that the rocker can be rotated with a minimum of lost rotatable motion in said shaft.

25 Figs. 6 to 8 inclusive illustrate a modification of the switch of the invention, and along with Figs. 9 and 10, also show alternative forms as well as alternate arrangements of the fixed and movable contacts.

A change is made in the rocker structure, but this 30 alteration does not change the manner in which it functions. In this case, the rocker which is preferably made of molded insulation material has incorporated therewith a metallic plate 209. The upper portion 210 of this plate is embodied in the body of the rocker and the lower 35 part 211 lies on the surface of the stem and carries a round stud or projection 212 which corresponds to the boss 110 on the previously described embodiment. The lower end of this plate is provided with oppositely disposed notches 213 which act as seats for the paws or 40 dogs. The extremity of the plate is curved to conform to the end of the rocker as in the previous embodiment. The plate has an operative portion therein in alignment with holes through the mid portion of the cross beam 40 through which the rocker support pin may extend. The 45 support pin in this case comprises a threaded shoulder bolt 215, the shoulder of which engages the center boss 41 and the threaded end of which may extend beyond the boss 41 and is locked by a lock nut 216. The head 217 holds the rocker on the pin. The above described 50 plate provides a sturdier rocker and one with surfaces that resist wearing through long periods of use.

It will also be noted that the dogs 195 which correspond to those (95) of the original embodiment are also 55 changed slightly. In this case, they are simpler in construction which is largely made possible by the use of a different type dog operating spring 199. The function is, however, the same. Each dog includes the rocker engaging arm 196 and the cam engaging arm 197. Each 60 is held with the arm 196 pressed toward the end of the rocker by a coil spring 199 disposed about the dog support pin 96 and having a hook formed on one end hooked about the arm 197 and the other end extending tangentially from the body at 200 and engaging the boss 100.

Another improvement which also results in economies 65 in manufacture resides in the operating shaft 160 which, in this case, has a main body 161 hexagonal in cross section. This eliminates the need for the keyways, since corresponding hexagonal holes are provided in the elements which turn with the shaft such as the cam 83 and 70 the spring operating element 86. The openings in the other elements obviously are large enough to permit the shaft to move therein without causing them to turn. In this instance, the key washer 82 is not needed because the hexagonal body is larger than the stem 63 and a thrust washer 82' replaces it. Also, the end of the body is re- 75

duced at 167 to provide a bearing surface for engagement in the back bearing bracket 168.

The bearing bracket 168 is also simplified in its contour as can best be seen in Fig. 6. It retains the center lug 135 but eliminates the arms 133 and 134. This is made possible by the substitution of another type of rocker return spring 232 for 130 and 132, which in this instance includes a helical body portion 230 of $1\frac{1}{2}$ or more turns, the ends 232 of which form arms one of which may engage the rocker support pin while the other engages the lug 105' on the spring drive element 86. The construction of this spring reduces the tendency to breakage due to fatigue because of the greater number of convolutions possible in the body. The spring drive element 86 is changed slightly in that the rotor return lever 105' is raised to a higher plane thereby enabling a smaller spring pressure to return the rotor to its original position.

As previously stated, any of the fixed contact strips may be removed if desired to provide a versatile switch without affecting the efficiency of its operation. Fig. 9 shows the center strips removed. In this case, the outer contacts are alternately made and broken when the rotor is operated.

The standard rotor contact 55 can be removed and a contact 34, constructed of an insulating material and having only the central portion enclosed within the body of the rotor, can be inserted in its place. The insertion of this dummy contact allows the same rotor contact spring assembly to be used while having the rotor operable at only one position.

In Fig. 10, one of the outer contacts has been removed and the center contact is provided with a single angularly disposed contact so that the center and only one side set of contacts is used. It will also be noted that the movable contacts in this instance also take a different form, being flat rather than curved, and that the fixed contacts are curved. This permits a better wiping action between the contacts reducing the contact resistance. This enables the user to make the necessary changes to provide a switch that can be used as a double pole single throw or double pole double throw. As shown in Fig. 10, both sets of contacts can be wired into the same circuit. Thus, since they are in different planes, the likelihood of breaking the circuit in the presence of mechanical shock is substantially reduced.

Figs. 11 and 12 show a modified form of back bearing plate and return spring which permits easier assembly and longer life for the spring.

The back plate is substantially the same conformation as that of Fig. 6. At the point on the plate where the bearing surface is provided for the shaft 160, however, three equally spaced lugs 208 are struck and are bent normal to the plate. The spring 205 in this instance is provided with a bent portion 210 which hooks over one of the lugs and then extends around the periphery of the other lugs for substantially one complete revolution. It then spirals outwardly for two or more revolutions and terminates in a severely bent part 207 which engages with the lug 209 of the plate. The plate and spring may be assembled as shown in Fig. 11, and then by rotating the shaft to move the spring operation member 86 beyond the lug 209 of the bearing plate and inserting the plate and spring, the spring is in position to pick up and engage the operation member when the switch is operated in the normal manner.

It will be apparent that the return spring operates as such only between the limits of its movement when turned by the operation member and returns the operation member to its normally neutral position at which time the spring 205 engages the lug 209 on the bearing plate and over travel in that direction by the operator member is only resisted by the rotor operating spring 90.

This structure enables the switch to be easily assembled, and it may be assembled in the plate in the reverse direction to that shown when it is desired to have the spring

return of the operating lever and its shaft in the other direction. It also enables the spring tension to be adjusted since the spring end 210 may be hooked over any one of the three lugs 209 on the bearing plate.

Inasmuch as the spring closely enfolds the lugs for one complete revolution and gradually spirals outward, there is realized a connection for the spring without sharp bends and therefore fatigue and breakage is reduced to a minimum.

It should also be noted that the plates which close the front and back are secured in place by screws that are threaded into the bosses 72 and 72' which are provided with blind holes 11. A gasket is usually interposed between the plate and housing, and with this construction a substantially moisture proof condition is realized.

It will thus be seen that I have provided a switch which is exceedingly versatile and rugged as well as simple. The action is such that a quick make and break is possible and the parts may operate over a long useful life and where breakages of the parts is reduced to a minimum due to the elimination of fatiguing parts. The construction of the rotor, with the head carrying the contacts and the stem with its included cam and dog plate, and the pivot being intermediate the head and stem, enables the same to be counterbalanced which not only affords a quicker operation but also help to eliminate bouncing upon making contact. It is also apparent that the versatility is increased by the ease of adjustment of both the contacts and the snap action mechanism, and that further the parts are readily accessible for examination or replacement should that be necessary.

Having thus described my invention, I am aware that numerous and extensive departures may be made therefrom without departing from the spirit of my invention as defined by the appended claims.

I claim:

1. An apparatus of the class described including spaced fixed contacts and movable contact carrying means for swinging movable contacts into and out of engagement with the fixed contacts, said movable contact carrying means being pivotally mounted and carrying the movable contacts on one end and having an operating stem comprising a projection, having curved surfaces and a portion extending beyond said projection and having dog engaging faces on opposite sides, spring means for engagement with said projection on opposite sides thereof, means for increasing the pressure of said spring means on said projection including a shaft and a spring operating member connected to and rotatable with the shaft and engaging the spring means, means to hold said stem against movement by the spring means until a predetermined pressure is built up therein by said spring operating means comprising a pair of dogs disposed on opposite sides of said stem each dog having an arm for engagement with said dog engaging face on the stem and means for urging said dogs with the arm into opposition with said face and cam means connected to and rotatable with said shaft and having a cam thereon for alternate engagement with said dogs to move them out of engagement with said face.

2. An apparatus of the class described including fixed contacts and a movable contact carrier for moving movable contacts into contact with said fixed contacts said carrier being pivotally mounted intermediate its ends and having a head portion carrying the movable contacts and a stem portion for cooperation with an operating means, said stem portion including a projection on one side having curved surfaces for connection to a moving means and a second portion extending beyond the projection and formed with dog engaging faces on opposite sides, said moving means including a shaft, a spring comprising a circular body portion surrounding and freely movable relative to the shaft and having a pair of arms extending outwardly therefrom and in tangential engagement with the curved surfaces on said projection, means carried by said shaft for alternately moving said arms to

70

stress said spring comprising a body in interlocking engagement with the shaft and having an offset arm extending between said spring arms, means to hold said stem portion against movement and to be released upon a predetermined movement of said shaft comprising a pair of dogs pivotally supported on opposite sides of said stem portion and each dog having an arm for engagement with one of said dog engaging faces on said stem portion and each dog having a second arm extending toward said shaft and spring means for biasing said dogs to move the face engaging arm opposite said face on said stem portion and cam means in interlocking engagement with said shaft having a cam surface for engagement with said second arm to alternately move said dogs out of engagement with the stem portion upon a predetermined movement of the shaft.

3. A switch of the class described including a housing having fixed contacts therein and a movable contact carrier for moving movable contacts into circuit making and breaking engagement with the fixed contacts, said movable contact carrier comprising a member pivotally supported by the housing intermediate its ends and having a head portion for carrying the movable contacts and a stem portion on the opposite end for cooperation with a snap action mechanism, said stem portion including a projection protruding from one side of the stem portion and adapted to cooperate with an operating spring, said stem portion extending beyond the projection and provided adjacent its end with dog engaging faces, said housing being provided with a bearing boss below said stem portion and an operating shaft journaled in said boss, said operating spring including a body portion disposed around said shaft and having a pair of arms extending outwardly therefrom and each being in tangential engagement with said projection on opposite sides thereof, a spring operating member disposed in interlocking engagement and movable with said shaft and having an offset arm extending between said spring arms adapted to alternately engage one or the other of said spring arms upon rotation of the shaft and upon movement by one of said spring arms, the other spring arm adapted to exercise increasing pressure on said projection, and means to hold said stem portion against movement in the face of increasing spring pressure comprising a pair of dogs pivotally connected to said housing on opposite sides of said stem portion, each of said dogs having an arm for alternate abutting engagement with said dog face on said stem portion and each having spring means engaged between each dog and the housing wall for urging said dogs for operative holding engagement with said stem portion, and a cam member disposed in interlocking engagement with said shaft and having a cam surface for alternate engagement with said dogs to move them alternately out of locking engagement with the stem portion.

4. A switch of the class described including a housing having fixed contacts therein and a movable contact carrier for moving movable contacts into circuit making and breaking engagement with the fixed contacts, said movable contact carrier comprising a member pivotally supported by the housing intermediate its ends and having a head portion for carrying the movable contacts and a stem portion on the opposite end for cooperation with a snap action mechanism, said stem portion including a projection protruding from one side of the stem portion and adapted to cooperate with an operating spring, said stem portion extending beyond the projection and provided adjacent its end with dog engaging faces, said housing being provided with a bearing boss below said stem portion and an operating shaft journaled in said boss, said operating spring including a body portion disposed around said shaft and having a pair of arms extending outwardly therefrom and each being in tangential engagement with said projection on opposite sides thereof, a spring operating member disposed in interlocking engagement and movable with said shaft and having an offset arm extending be-

tween said spring arms adapted to alternately engage one or the other of said spring arms upon rotation of the shaft and upon movement by one of said spring arms, the other spring arm adapted to exercise increasing pressure on said projection, and means to hold said stem against movement in the face of increasing spring pressure comprising a pair of dogs pivotally connected to said housing on opposite sides of said stem portion, each of said dogs having an arm for alternate abutting engagement with said dog face on said stem portion and each having spring means engaged between each dog and the housing wall for urging said dogs for operative holding engagement with said stem portion, and a cam member disposed in interlocking engagement with said shaft and having a cam surface for alternate engagement with said dogs to move them alternately out of locking engagement with the stem portion, and means for supporting an end of said shaft comprising a plate seated on the housing wall and having an opening for receiving the end of the shaft, and means for biasing the shaft to an extreme rotated position comprising a second spring having a body disposed about the shaft and a pair of outwardly extending arms prestressed to an open position and a second offset arm on said operating member engaged on the outside of one of said spring arms and means on said plate disposed for engagement with the other arm, said arms when disposed between said second offset arm and said lug being tensioned to move said second arm away from said lug.

5. A switch including spaced apart fixed contacts and a swingable contact carrier arranged to be swung to bring movable contacts into contact with the fixed contacts, said swingable carrier including a head portion for supporting the movable contacts and a stem part projecting from said head, pivot means for pivotally supporting the carrier below said head and spaced from the end of the stem part, said stem part being provided with a plate embedded in the stem part and having a part coextensive with the end of the stem part supporting an operating pin and formed to provide pawl engaging seats, means for engagement with said stem part to swing the carrier including an operating shaft, a spring having a pair of arms engaging said operating pin, a lever connected to said shaft and having a portion extending between said spring arms and movable to move one of said arms away from said spring and to increase the tension on the other arm, a cam carried by said operating shaft, a pair of pawls each engageable with said stem part upon movement to alternate positions, said cam means being arranged for alternate engagement with said pawls to release said pawl from holding engagement with the stem upon a predetermined movement of the shaft.

6. A switch including spaced apart fixed contacts and a swingable contact carrier arranged to be swung to bring movable contacts into contact with the fixed contacts, said swingable carrier including a head portion for supporting the movable contacts and a part projecting from said head, pivot means for pivotally supporting the carrier below said head and spaced from the end of the head and said projecting part, said part being provided with a plate embedded therein and having a part coextensive with the end of the part supporting an operating pin and formed to provide pawl engaging seats, means for engagement with said part to swing the carrier including an operating shaft, a spring having a pair of arms engaging said operating pin, a lever connected to said shaft and having a portion extending between said spring arms and movable to move one of said arms away from said spring and to increase the tension on the other arm, a cam carried by said operating shaft, a pair of pawls each engageable with said pawl seat upon movement to alternate positions, said cam means being arranged for alternate engagement with said pawls to release said pawl from holding engagement with the part upon a predetermined movement of the shaft.

7. An operating means for a switch including a housing

having front, rear and side walls and having fixed contacts, and a movable contact carrying member for moving movable contacts into and out of engagement with the fixed contacts, said movable contact member including a rotor having a head portion for supporting the movable contacts and pivot means for pivotally supporting said member intermediate its ends, said member having an operating stem disposed on the opposite side of said pivot to the contacts and including a plate embedded in the stem and having a projection thereon for engagement by a moving means and seats disposed below the projection for a stem holding means, said moving means including an operating shaft journaled in the front wall and a bearing plate for the rear end of the shaft, an operating member carried by said shaft and connected thereto and rotatable therewith and having an outwardly extending spring operating member, a spring including a body portion surrounding the shaft and having outwardly extending arms which are tensioned by the body portion to resiliently force the arms toward each other, said arms being in engagement with the projection on said stem and said operating member extending between said spring arms and arranged to increase the pressure of one of said spring arms on said projection by moving the other spring arm away from the projection, pawl means supported by said housing on opposite sides of said housing and each having a portion for engagement with said stem when the stem is moved furthest away from the pawl support, and cam means connected to and rotatable with said operating shaft and arranged to engage said pawl and release it from said seat on said stem upon a predetermined movement of said shaft.

8. A switch comprising a housing including side walls, a fixed contact carrier disposed in the one end of said housing and supporting fixed contacts in spaced relation to each other, a bridge portion for said housing disposed spaced from said fixed contacts and a movable contact carrier for carrying and moving movable contacts into and out of contact with the fixed contacts pivotally supported on said bridge, said movable contact carrier having a portion extending from said pivot point toward the other end of the housing and being formed on the end with pawl engaging seats and having an outwardly extending projection above said seats, means for moving the carrier between alternate positions including a shaft rotatably disposed in the end of the housing, spring means for exerting pressure on opposite sides of said projection engaging said boss, a spring tensioning member connected to said shaft and having a portion arranged for alternate engagement with said spring means to move one part away from the projection and increase the pressure on the other part, pawl means disposed on opposite sides of the housing and having pawl arms each arranged to alternately engage said seats, cam means on said shaft arranged for alternate engagement with said pawls to release said pawls from holding engagement upon predetermined rotation of the shaft.

9. A switch comprising a housing including side walls, a fixed contact carrier disposed in the one end of said housing and supporting fixed contacts in spaced relation to each other, a bridge portion for said housing disposed spaced from said fixed contacts and a movable contact carrier for carrying and moving movable contacts into and out of contact with the fixed contacts pivotally supported on said bridge, said movable contact carrier having a portion extending from said pivot point toward the other end of the housing and being formed on the end with pawl engaging seats and having a projection on the side above said seats, means for moving the carrier between alternate positions including a shaft rotatably disposed in the end of the housing, spring means for exerting pressure on opposite sides of said projection engaging said projection, a spring tensioning member connected to said shaft and having a portion arranged for alternate engagement with said spring means to move one part away from the pro-

jection and increase the pressure on the other part, pawl means disposed on opposite sides of the housing and having pawl arms each arranged to alternately engage said seats, cam means on said shaft arranged for alternate engagement with said pawls to release said pawls from holding engagement upon predetermined rotation of the shaft, a second spring means for said shaft including a spring surrounding the shaft and having an end connected with the housing to hold it against movement and another end for engagement with said tensioning member.

10. A switch comprising a housing including side walls, a fixed contact carrier disposed in the one end of said housing and supporting fixed contacts in spaced relation to each other, a bridge portion for said housing disposed spaced from said fixed contacts and a movable contact carrier for carrying and moving movable contacts into and out of contact with the fixed contacts pivotally supported on said bridge, said movable contact carrier having a portion extending from said pivot point toward the other end of the housing and being formed on the end with pawl engaging seats and having a projection on the side above said seats, means for moving the carrier between alternate positions including a shaft rotatably disposed in the end of the housing, spring means for exerting pressure on opposite sides of said projection engaging said projection, a spring tensioning member connected to said shaft and having a portion arranged for alternate engagement with said spring means to move one part away from the projection and increase the pressure on the other part, pawl means disposed on opposite sides of the housing and having pawl arms each arranged to alternately engage said seats, cam means on said shaft arranged for alternate engagement with said pawls to release said pawls from holding engagement upon predetermined rotation of the shaft, a second spring means for said shaft including a spiral spring surrounding said shaft and having an inner end connected to said housing to hold it against movement and the other end connected to said spring tensioning member.

11. A switch comprising a housing, fixed contacts supported in spaced relation to each other in one end of the housing, movable contact means pivotally supported from the housing and having movable contacts swingable into and out of engagement with said fixed contacts said movable contact means having an operating portion extending from said pivot point opposite to the contact carrying end and including a part having pawl engaging faces formed on opposite sides, a projection formed on the face of said part, pawls pivotally arranged on opposite sides of the housing and having spring means for each pawl to urge it into engagement with one of said seats, said pawls being disposed to hold the operating portion in alternate extreme positions against swinging, means for engagement with said projection to exert spring tension thereon including a shaft rotatably journaled in the lower part of the housing, a spring surrounding said shaft and having a pair of outwardly extending arms engaging said projection and exerting spring tension on opposite sides thereof, means to increase the spring tension on one of the arms comprising a lever keyed to the shaft and having an offset arm disposed between said spring arms and movable with said shaft to move one of the other of said arms away from the projection and increase the pressure on the other arm, a pawl release member for alternately releasing said pawls and permitting the spring to move the operating portion to another position secured to said shaft and having a cam surface for engagement with an operation of said pawls, means to return said shaft to its original position comprising a spring having one end in engagement with the housing, a plate disposed in the housing and having a lug extending inward toward the operating member, one end of said shaft return spring being engaged with said lug and arranged to be engaged by said operating member to extend pressure against the

13

operating member when it is moved and to return it to its original position.
